C. DE MARTIN.
 CONNECTING AND DISCONNECTING MECHANISM FOR EMBROIDERING MACHINES.
 APPLICATION FILED DEC. 4, 1919.

1,361,520.

Patented Dec. 7, 1920.

 Max. Ortmann

UNITED STATES PATENT OFFICE.

CELESTE DE MARTIN, OF WEST NEW YORK, NEW JERSEY, ASSIGNOR TO ROBERT REINER, INCORPORATED, OF WEEHAWKEN, NEW JERSEY.

CONNECTING AND DISCONNECTING MECHANISM FOR EMBROIDERING-MACHINES.

1,361,520.

Specification of Letters Patent.

Patented Dec. 7, 1920.

Application filed December 4, 1919. Serial No. 342,511.

To all whom it may concern:

Be it known that I, CELESTE DE MARTIN, a subject of the King of Italy, residing at 599 22d street, West New York, in the county 5 of Hudson and State of New Jersey, have invented certain new and useful Improvements in Connecting and Disconnecting Mechanism for Embroidering-Machines, of which the following is a specification.

10 My invention relates to embroidering machines and has for its object to provide means whereby without arresting or disconnecting the embroidering-machine-operating mechanism from its driving mechanism or 15 even without reducing the speed of the machine the operation of one set of embroidering implements, such as the stitching needles, borers, or the like, may be changed into that of others, or the embroidering implements 20 may be temporarily arrested, as e. g. the stitching needles may be stopped outside of the design in order to give the embroidery frame while the machine is in operation any movement without affecting 25 the design.

My invention consists in that the movement of the implements controlling the roller is so supported above the cam, that it may freely move bodily in vertical direction 30 relative to the latter and that to hold it in close contact with the cam during the operation of the implements a lock is employed which, by a short motion, can be positioned to lock or unlock said roller.

35 While I shall in the following describe two different forms of construction for accomplishing my object, I wish it to be understood that various other forms of construction may be designed for accomplishing the 40 same object and function, without departing from the principle of my invention.

In the accompanying drawing which forms part of this specification and in which similar reference characters denote corresponding parts, Figure 1 is a sectional end elevation of a part of an embroidering machine equipped with my novel device, the machine being shown in a more or less diagrammatic view; Fig. 2 is a front sectional 45 elevation of a part of the machine, equipped with my novel device, and Fig. 3 is a similar view as Fig. 1, showing a modified construction of the device.

Referring to the drawing more in detail, 50 a denotes the main driving shaft of the ma-

chine which drives the cam b controlling the embroidering implements. With very long machines, in order that the implements operate uniformly at all points of the length of the machine, two cams b b are used, one 60 at each end of the machine, both cams being driven from the same shaft a.

In the present example we shall, for simplicity's sake, describe the device in connection with the stitching needles, it being obvious that the device without any material changes may be applied in connection with bорers, take-ups, etc.

Accordingly, let c denote one of the set of stitching needles, adapted to operate through 70 the fabric x—x carried by the usual fabric frame (not shown). The needles are carried by the needle bar d extending throughout the length of the machine and whose reciprocatory motion is effected by the cams 75 b b, through the medium of bars e connected to the needle bar d by bell cranks f. Each of the bars e carries two rollers i and j of which roller i engages the inner surface and j, the outer face of the cam. These 80 rollers, when in close contact with the opposite faces of the cam will transmit positive motion to the needle bar d.

To temporarily interrupt the transmission of motion to the implements without 85 stopping the shaft a or affecting the operation of the machine in any way whatsoever, each roller j is carried by an arm k which, like a plunger, is supported in the corresponding bar and is capable of moving 90 therein vertically toward and away from the cam. To this end each bar e is formed at its lower end with a vertical guide groove e' in which the plunger arm k is so fitted as to be capable of moving freely therein 95 in vertical direction. Each bar e has an additional guide groove e², extending transversely to the guide groove e' and serving to receive a slide l whose movement is controlled from the jacquard as will be hereinafter described. The slide l is provided with a cross piece or block m which is adapted in normal position, that is, when the implements are to be in operation, to register with the upper end of the plunger arm k and act 100 as a stop or lock, holding the plunger arm stationary in a position where the roller j will be in close contact with the cam b.

A rod p controlled from jacquard pin q and adapted to be operated from a continu- 110

ously swinging lever arm *r* in well known manner operates the slides *l* through a pair of bell cranks *g* arranged on a common shaft *n* extending through the length of the machine so that a slight motion of the rod *p* will suffice to move the slides into locking or unlocking position.

Since the pressure exerted by the cams *b* on the plunger arms *k* is directed vertically 10 against the slide or stop *m*, the jacquard mechanism will not be affected, and little force will be required to move the slide. When the plunger arms *k* have been released 15 the cams will be allowed to continue their rotation without imparting movement to the implements.

In the modification shown in Fig. 3, the slide *l* is replaced by a slotted lever *s* which 20 engages a pin *t*, projecting from a toggle mechanism consisting of two arms *u* *u'* of which one, *u*, is pivoted to the bar *v* and the other, *u'*, to the upper end of the plunger arm *k*. The bell crank *g* is pivotally connected to the slotted or looped arm *s*, so that 25 the latter is operated from the jacquard controlled rod *p* in the same manner as the slide *l* of the first construction.

When the toggle mechanism *u*, *t*, *u'* is in stretched position *i. e.*, when the two arms 30 thereof are in line with one another, the plunger arm *k* is locked against vertical movement relative to *v*. But when through the displacement of the looped arm *s* the toggle is collapsed, the plunger arm *k* is released and the roller allowed to move freely 35 in the guide *v'* of the bar *v*. As in the first modification, the slotted arms at both ends of the machine are connected through a spindle *n* and bell cranks *g* so that the locking and unlocking of the plunger and roller *j* at the jacquard end of the machine is instantaneously and synchronously transmitted to the plunger and roller at the opposite end of the machine.

45 What I claim and desire to secure by Letters Patent is:

1. In an embroidering machine, the combination with embroidering implements and a driven cam for operating the latter, of a 50 member operatively connected to said implements and having a roller adapted to remain constantly in contact with said cam but capable of moving rectilinearly in a vertical direction in said member, and means for locking said roller against vertical movement relative to said member so as to transmit motion to the latter.

2. In an embroidering machine, the combination with embroidering implements and 60 a driven cam for operating said implements, of a member operatively connected to said implements and having a roller adapted to remain constantly in contact with said cam but capable of moving rectilinearly in a vertical direction in said member, and auto-

matically controlled means for temporarily locking said roller against vertical movement relative to said member so as to transmit motion to the latter.

3. In an embroidering machine, the combination with embroidering implements and a driven cam for operating said implements, 70 of a member operatively connected to said implements and having a roller adapted to remain constantly in contact with said cam but capable of moving rectilinearly in a vertical direction in said member, and an automatically controlled slide movable across the path of said roller and capable of locking 75 said roller against vertical movement relative to said member so as to transmit motion 80 to the latter.

4. In an embroidering machine, the combination with embroidering implements and driven cams, of members operatively connected to said implements and having vertical guides, rollers movably supported in 85 said guides and adapted to remain constantly in contact with their respective cams and automatically controlled means for 90 locking each roller against vertical movement relative to the respective member and automatically controlled common means for operating the said locking means synchronously.

5. In an embroidering machine, a driven cam, an implement operating bar, two rollers carried by said bar to engage the inner and outer surface of said cam, the outer roller being adapted to remain constantly in 95 contact with said cam and to be bodily movable in said bar in a vertical direction, and a member movable across the vertical path of said outer roller to lock the latter against vertical movement relative to said bar to 100 transmit motion to the latter.

6. In an embroidering machine, a driven cam, an implement operating bar, two rollers carried by said bar to engage the inner and outer surfaces thereof, the outer roller being adapted to remain constantly in contact with said cam and to be bodily movable in said bar in a vertical direction and an automatically controlled slide movable 110 across the vertical path of said outer roller to lock the latter against vertical movement 115 relative to said bar.

7. In an embroidering machine, the combination with driven cams, of implement operating bars operated from said cams, a plunger arm capable of moving vertically in each bar, a roller carried by each plunger arm, means movable across the path of each plunger arm for locking the latter against vertical movement relative to the corresponding bar, jacquard controlled means for operating the said last named means at one 120 end of the machine, and means for transmitting 125 said jacquard controlled operation to the other end of the machine.

8. In an embroidering machine, a cam operated bar having a vertical guide and a cross guide, a plunger arm movable in said vertical guide, a roller carried by said plunger arm, a slide movable in said cross guide and adapted to act as a stop or lock for said plunger arm and jacquard controlled means operatively connected to said slide.
9. In an embroidering machine, the combination with embroidering implements and a driven cam, of a member operatively connected to said embroidering implements and having a vertical guide, a roller movably supported in said guide and adapted to remain 15 constantly in contact with said cam and means for locking said roller against vertical displacement relative to said member.
10. In an embroidering machine, the combination with embroidering implements and a driven cam, of a member operatively connected to said embroidering implements and having a vertical guide, a plunger freely movable in said guide, a roller carried by 20 said plunger and adapted to remain constantly in contact with said cam and means for locking said plunger to said member.
11. In an embroidering machine, the combination with embroidering implements and 25 a driven cam, of a member operatively connected to said embroidering implements a roller rectilinearly movable in said member

and adapted to be constantly in contact with said cam and means for locking said roller to said member.

35

12. In an embroidering machine, the combination with embroidering implements and a driven cam, of a member operatively connected to said implements and having a vertical guide, rollers carried by said member 40 to engage the inner and outer surfaces of said cam, the outer roller being rectilinearly movable in said vertical guide and adapted to be constantly in contact with said cam and automatically controlled means for locking 45 said outer roller against vertical displacement.

13. In an embroidering machine, the combination with embroidering implements and a driven cam, of a member operatively connected to said implements, a roller freely and rectilinearly movable in said member and adapted to be constantly in contact with said cam and a locking member movable across the rectilinear path of said roller to 50 operatively connect the latter to said member.

In testimony whereof I affix my signature in presence of two witnesses.

CELESTE DE MARTIN.
